K. EVERTZ

OPPOSITE REPLICA MODELING MACHINE

Filed Aug. 28. 1926

INVENTOR,
Knutte Evertz.
BY David E. Lain,
ATTORNEY.

UNITED STATES PATENT OFFICE.

KNUTE EVERTZ, OF BELLINGHAM, WASHINGTON.

OPPOSITE-REPLICA MODELING MACHINE.

Application filed August 28, 1926. Serial No. 132,305.

My invention relates to improvements in opposite-replica modeling machines, and the object of my improvement is to produce a simple machine for shaping in clay an opposite duplication of a model.

I attain this object with the mechanism illustrated in the accompanying sheet of drawings in which Figure 1 is a side elevation of my modeling machine in operative position, Fig. 2 is a front elevation of Fig. 1 and Fig. 3 is a plan view of Fig. 2.

Similar characters refer to similar parts throughout. Certain parts are broken away for lack of space or to show other parts hidden thereby.

A vertical guide plate 4 has lugs 5 in which are holes for screws with which plate 4 is fastened to a wall or other upright structure not shown. In plate 4 is a vertical row of spaced holes 6. Mounted for vertical reciprocation in guide plate 4 is a slide base 7. On each end of base 7 is a stud 8 having a foot 9 which is fastened to said base with screws. Studs 8 are at right angles with base 7 and on the facing side of each is mounted for reciprocation one of end frame members a^{10} , each having a socket 10 at each end thereof. In opposite sockets 10 are fastened parallel side frame members 11. The frame a^{10} , a^{11} , 11, 11 is thus mounted for reciprocation between studs 8, 8 in the directions indicated by the arrows. On side frame members 11, 11 are mounted for vertical reciprocation upper crosshead 12 and lower crosshead a^{12} . Hand lever 13 is pivoted on a bracket fastened to base slide 7 at 14 and to one end thereof is pivoted pin a^6 reciprocable in a hole in base 7 and engageable in any one of holes 6 in slideway 35 or guide plate 4. Base 7 is set at the desired height by withdrawing pin a^6 by pressing on hand lever 13 against spring 15, which is set to react between said lever 13 and base 7, then when base 7 has been moved to the desired location in elevation pin a^6 is allowed to engage in the nearest hole 6. Tool arm 16 and stylus arm 17 are mounted for oscillation at 18 on crosshead 12. Link 19 is pivoted on arm 16 at a^{19} , and link 20 is pivoted on arm 17 at a^{20} and both links are mounted for oscillation on crosshead a^{12} at 21. Pivots a^{19} and a^{20} are equidistant from bearing 18. The construction here being such that an angular movement of arm 17 will cause a movement of the same angle of

arm 16 and movements causing arms 16 and 17 to separate will cause crossheads 12 and a^{12} to approach while movements causing said arms to approach will cause said crossheads to separate from each other. Stylus a^{17} is clamped by screw clamp b^{17} in the outer end of arm 17, and tool a^{16} is fastened by screw clamp b^{16} in the outer end of arm 16 at the same distance from bearing 18 as is stylus a^{17} . Thus, when stylus a^{17} is moved through an arc around bearing 18 tool a^{16} is caused to move through an equal arc around the same center. Also, when stylus a^{17} is moved up or down by causing crossheads 12 and a^{12} to reciprocate on guide frame members 11, 11 tool a^{16} is caused to move up or down an equal amount. Then, any plane figure described by stylus a^{17} will cause tool a^{16} to describe the same sort of figure in the vertical and the opposite of the same figure in the horizontal inasmuch as stylus a^{17} and tool a^{16} move equally and opposite in the horizontal. When frame a^{10} , 11, 11 is moved forward or backward on studs 8, 8 stylus a^{17} and tool a^{16} are moved in the same direction to an equal amount. From all of which it appears that any motion in space described by stylus a^{17} is exactly duplicated by tool a^{16} in the vertical, and in the horizontal forward and backward, and also in the horizontal to the right and left except that the later movements in the horizontal are in opposite directions.

Arcuate movements of stylus and tool as well as horizontal movements thereof forward and backward are made with slight effort since they are neither aided nor opposed by the weight of the mechanism. But vertical movements of said point and tool are opposed or aided by the weight of crossheads 12 and a^{12} added to the weight of arms 16 and 17 and links 19 and 20. To counterbalance these latter parts counterweight 23, of equal weight therewith, is hung on string 25 which is passed over sheave 24 and fastened to bracket 26 attached to crosshead 12. Weight 23 is mounted for vertical reciprocation by bearings a^{23} slidable on guide rod 22. Guide rod 22 is fastened at top and bottom to frame ends 10, 10. Sheave 24 is mounted for revolution in a bearing in bracket a^{24} fastened to upper frame bearing member a^{10} . Thus, both said crossheads 12 and a^{12} , and weight 23 are installed on frame a^{10} , a^{10} , 11, 11 for equal and opposite move- 110

ments in the vertical, and said weight is a suitable counterpoise for arms 16 and 17 and said crossheads. In this manner the vertical movements of stylus and tool are made without sensible aid or hindrance from gravity.

From this description it should now be clear that when a model is fastened within the range of the point of stylus a^{17} and a clay shape is fastened within the reach or 10 range of tool a^{16} and the point of the stylus is moved over the surface of the model then the tool will cut away the clay down to a surface exactly corresponding to those parts of the model over the surface of which the 15 stylus has been moved except the model design is duplicated in the clay in a relatively opposite or as-in-a-looking-glass manner. By continuing to copy a number of proximate areas of the model on the clay 20 the precise character, dimensions, and relative location of the lines and surfaces of the model are sufficiently developed in the clay that the desired design thereon may be completed by hand without losing the freedom 25 of lines and surfaces natural to the original and so difficult to reproduce by hand in an exact copy thereof. It may be noted that this machine is especially suited for completing that class of designs in which there is a 30 duplication of the design on opposite sides of a medial line.

In Fig. 1 the arrows indicate the out and in direction of the movements of frame a^{10} , a^{10} , 11, 11; while in Fig. 2 a second position for arms 16 and 17 is shown at 16', 17' in dotted lines wherein upper crosshead remains stationary, and also weight 23 remains stationary. Also said arms are shown in dotted lines in a third position at 16'', 17'', more closely folded to the frame, in 40 which the upper crosshead has been moved downward and the counterweight moved upward to 23''. In this way all parts of the model may be gone over within the range of one setting of base 7 as held by pin a^6 in 45 one of holes 6. Then other settings of said base are made with said pin engaged in other of holes 6 till the entire height of the model has been copied.

Having thus disclosed my invention, what

I claim as new therein and desire to secure by Letters Patent is,—

1. In combination, a vertical guideway, a base slidable on said vertical guideway, releasable means to retain said base in desired positions on said slideway, horizontal guide studs fastened to said base in parallel relation, a frame having vertical guide rods mounted for horizontal reciprocation on said guide studs, upper and lower crossheads 55 mounted for vertical reciprocation on said vertical guide rods, a pair of arms mounted for oscillation on a common pivot in said upper crosshead, a pair of equal links mounted for oscillation on a common pivot in said lower crosshead each pivoted to one of said arms at an equal distance from said common pivot thereof, a stylus fastened in the end of one of said arms, and a clay-working tool 60 fastened in the end of the other of said arms 65 at the same distance from said common pivot thereof as said stylus. 70

2. In combination, a vertical guideway, a base slidable on said vertical guideway, releasable means to retain said base in desired positions on said slideway, horizontal guide studs fastened to said base in parallel relation, a frame having vertical guide rods mounted for horizontal reciprocation on said guide studs, upper and lower crossheads 75 mounted for vertical reciprocation on said vertical guide rods, a pair of arms mounted for oscillation on a common pivot in said upper crosshead, a pair of equal links mounted for oscillation on a common pivot in said lower crosshead each pivoted to one of said arms at an equal distance from said common pivot thereof, a stylus fastened in the end of one of said arms, a clay-working tool fastened in the end of the other arm at the 80 same distance from said common pivot thereof as said stylus, a vertical guide rod fastened to said frame, a counterweight mounted for reciprocation on said guide rod, a bracket 85 fastened to the upper end of said frame, a sheave mounted for revolution on said bracket, and a string fastened to said upper crosshead passed over said sheave and fastened to said counterweight. 90 95
